Application June 18, 1945, Serial No. 600,122

7 Claims. (Cl. 255—1)

1

This invention relates to improvements in well recording mechanisms, particularly for determining and recording information obtained during the drilling of deep wells.

To operate well drilling equipment in the most efficient manner, the driller should have readily available several types of information throughout the process of the drilling, particularly the amount of time required to drill through each foot of the formation, the speed at which the rotary table is driven during the drilling of each foot of formation, and the mud pump pressure at the time of drilling each specified foot of formation. It is also desirable to know the time when the drilling was stopped and the length of time required to remove the drill stem from the bore hole of the well.

With this information determined and recorded, an experienced driller is able to determine therefrom the progress and characteristics of the drilling operation and particularly the efficiency thereof. By recording this information accurately on a log strip, it can be used to improve the drilling procedure of the well or applied in the drilling of other wells under similar conditions.

The present invention is designed primarily for determining and recording in chronological relation the most important types of data that will be useful to the operator or driller in determining the proper drilling procedure for most efficient operation or to change the procedure used as may be desirable.

The object of this invention is to provide for the automatic determining and recording on a log sheet or record strip in chronological order certain data which results as a function of the drilling operation to make this available to the driller both as the drilling progresses and from time-to-time thereafter whenever its use may be desirable.

Another object of the invention is to simplify and improve recording mechanism for this purpose to enable such mechanism to be manufactured inexpensively, operated without difficulty, attached readily to the drilling equipment to operate in synchronism therewith and yet will give dependable and permanent records of the various actions involved in the drilling operation, recording these chronologically on a chart or record strip so as to make them available to the driller when needed.

The invention is embodied preferably in the form of an electrically operated well recording mechanism which functions in response to the

2

several elements of the drilling equipment to correlate the actions thereof on a log sheet or record strip, so as to make these results available to the driller.

5 This embodiment is shown for purposes of illustration in the accompanying drawings in which:

Fig. 1 is a side elevation of a well drilling rig with parts broken away and illustrating diagrammatically the recorder associated therewith;

Fig. 2 is a perspective view of the recording instrument with the cover removed and with parts broken away and in section;

10 Fig. 3 is a vertical section through the strip perforator thereof;

Fig. 4 is a side elevation of a perforator lever detached;

Fig. 5 is a side elevation of a perforator plate detached;

Fig. 6 is a diagrammatic view of the perforator devices and their wiring diagrams;

Fig. 7 is a side elevation of a contact device that is operated in synchronism with the drilling equipment;

Fig. 8 is a top plan view thereof;

Fig. 9 is a top plan view of a stop switch device;

Fig. 10 is a plan view of a revolution counter switch device; and

Fig. 11 is a fragmentary side elevation of a portion thereof on the line 11—11 of Fig. 10.

This invention is adapted to be used in connection with a rotary well drilling rig which has the customary mud pump, rotary table, draw-

35 works and derrick. The mechanism is interconnected to operate in conjunction with the several devices in order to determine and record in correlation the functions of these several devices as, for instance, the speed of the rotary table, the speed of the mud pump, the distance the drill stem is lowered, and the distance that the drill stem is raised from the bore hole of the well. These functions are correlated to the time that it takes to drill each specific foot of formation and all of such information is recorded on a log sheet or record strip available to the driller at all times.

40 Referring to Fig. 1, the numeral 1 indicates the base from which the conventional derrick 2 is in upstanding relation. The derrick 2 has mounted on the upper end thereof a conventional crown block assembly generally indicated at 3 that includes rotary sheaves mounted on a cross shaft 4, and over which sheaves a cable 5 extends for suspending a swivel 6 in the usual

manner. The swivel 6 carries the drill stem 7 that extends downwardly in the well and on the lower end of the drill stem is located the drill bit that is turned to accomplish the drilling operation.

The drill stem 7 is rotated during the drilling operation by a rotary table 8 mounted on the base 4. The rotary table 8 is driven by draw-works 9 which also includes hoisting mechanism connected with the cable 5 that suspends the drill stem 7 to raise or lower the drill in the well as desired, the drill being lowered normally during the rotation of the drill stem for drilling purposes.

The drill stem 7 ordinarily is hollow and it is customary to force drilling mud down through the drill stem during the drilling operation, discharging the mud at the bit for upward flow around the drill stem to carry the earth cuttings to the top of the well and for sealing the side walls thereof.

A mud pump designated generally at 10 is provided for this purpose and connected through a pipe 11 with the swivel 6 to supply mud under pressure to the drill stem 7 at its upper end. The pump 10 may be driven by any suitable form of motor generally indicated at 12.

This mechanism described above is the conventional well drilling equipment and referred to herein for purpose of illustration to show the manner of applying this invention in connection therewith.

Associated with the drilling equipment is a recording device generally illustrated at 14 which may be mounted in some convenient position near the drilling equipment where it may be accessible and visible to the driller for inspection purposes from time-to-time as the drilling progresses. A transparent cover 15 is detachably mounted to enclose the record sheet or strip and may carry suitable indicia in properly disposed relation to the different parts of the record strip so as to indicate to the driller the nature of the information recorded thereon.

The recording device is shown more in detail in Figs. 2 to 5. A support 16 has the cover 15 detachably mounted thereon and carries the operating parts of the recorder as shown particularly in Fig. 2. A record strip 17 extends from a supply roll 18 journaled on the base 16 over a guide roll 19 to a winding roll 20, these rolls being properly journaled on the base 16 and mounted for turning movement upon upward movement of the record strip 17 as wound upon the roll 20. This winding action is accomplished by the rotation of the roll 20 by power, being operated by a motor 21 connected therewith, so as to wind up the record strip at a uniform rate during the drilling operation. A clock motor may be used satisfactorily for this purpose.

The record strip is divided transversely into columns for indicating respectively different types of information desired by the driller, such as "Time," "R. P. M. Rotary Table," "R. P. M. Pump," "Raising Drill Stem" and "Depth in Feet."

While these respective designations indicate the usually desired information, it is evident that other characteristics may be determined as desired and the system changed accordingly to vary the type of information indicated and recorded thereby.

The record strip extends upwardly over a back support 22 between the latter and a die plate 23. The die plate 23 is mounted in spaced relation

from the back support 22 to provide a vertical slot therebetween through which the record strip 17 may be guided and held for the punching operation. The support 22 and die plate 23 are provided with aligned orifices 24 and 25, respectively, arranged in positions along the die plate 23 to correspond with the respective columns of the record strip 17, as will be evident from Figs. 2 and 5. Each pair of aligned orifices 24 and 25 is adapted to receive and guide a punch 26 mounted for reciprocating movement therethrough and carried by a plunger 27 which forms the core of a solenoid 28. One punch 26 and solenoid 28 are provided for each pair of orifices 24 and 25 spaced along the die plate 23 according to the number of orifices provided for the respective columns of information to be recorded on the strip 17 which may be varied as desired. The respective solenoids 28 are secured to the back face of the plate 22 as shown in Fig. 3.

Each plunger 27 has a loose connection with a bifurcated portion 29 of a lever 30 that extends upwardly behind the back plate 22. The lever 30 is pivotally mounted intermediate its ends on a flange 31 formed on the plate 22, by means of a slot 32 in the lever which receives a pin 33 carried by the flange 31, thus forming a loose pivotal support for the lever capable of swinging movement relative thereto under the influence of the solenoid 28. The upper end of the lever 30 has a coiled spring 34 connected therewith normally tending to move the lever to the position shown in Fig. 3, where its movement is limited by a guide screw 35 located in the bifurcation 29 of the lever. The guide screw 35 may be adjusted to vary the withdrawn position of the punch 26 relative to the orifice 24. In this position, the lever 30 will hold the punch 26 in its retracted position, as shown in Fig. 3, clear of the record strip allowing movement of the latter. When the solenoid 28 is energized, the plunger 27 will be attracted to move forward therein, projecting the punch 26 through the orifices 24, 25, thereby punching a hole in the record sheet to form an indication of respectively different actions of the well drilling equipment.

The several punching devices are spaced transversely of the record sheet 17 to register with the respective columns thereof as will be evident from Fig. 2, and are respectively operated through a control circuit as shown in Fig. 6 in response to respective control devices as hereinafter described.

The recording device has provision also for recording on the record strip 17 the depth in feet of the drilling operation in the well. This is shown in Fig. 2, as including a printing attachment 36 having rotatable numbering rolls generally designated at 36', of a character well-known in the printing art, and operated by a solenoid 37. This printing device 36 is mounted on the front face of the die plate 23 which plate is provided with an opening 38 therein (Fig. 5) for printing action of the device in contact with the front face of the record strip 17 as will be evident from Fig. 2. The recording of total footage by this printing device may be at intervals of ten feet, if desired, or at other distances which may be practical for particular applications of this invention. Intermediate footage markings may be provided by a perforator punch of the character described above.

The record strip is also preferably imprinted with time designations which are initially applied thereto or applied by a printing device incor-

porated as a part of the recording mechanism, which is not shown because such devices are well-known in the art of recording mechanisms and their use will be evident to one skilled in the art.

These devices are adapted to be operated in timed relation with the lowering movement of the drill stem 7 in the well as the drilling progresses. To synchronize this action, I have provided a switch device, generally designated at 39 in Fig. 1, at the top of the derrick to be operated in accordance with the lowering or raising movements of the drill stem. This switch device 39 is shown more in detail in Figs. 7 and 8.

This switch device 39 is operated by a sprocket chain 40 which extends from the sheave shaft 41 of the crown block 3 and passes over a sprocket 41 of the switch device (Figs. 7 and 8), journaled loosely on a shaft 42 rigidly fixed against rotation in the switch device and supporting the operating parts thereof. Ratchet wheels 43 and 44 are journaled on the shaft 42 on opposite sides of the sprocket 41. The ratchet wheels 43 and 44 have the teeth thereof turned in opposite directions so as to function in opposed directions. These ratchet wheels are confined by pins 45 to their operating positions while free to turn on the shaft 42.

Pawl 46 and 47 are pivotally mounted on respective opposite sides of the sprocket 41 and are turned in opposite directions corresponding with the directions of the respective ratchet wheels 43 and 44. Torsion springs 48 act on the respective pawls 46 and 47 to hold these in engagement with the ratchet wheels 43 and 44.

Fixed to the respective ratchet wheels 43 and 44 on the outer sides thereof and projecting radially therefrom, as shown in Fig. 7, are resilient switch arms 49 and 50 in position for wiping relation with pairs of contacts 51 and 52 mounted on upstanding supports 53 in the switch device. Inasmuch as the desired time of contact is of short duration, the wiping faces of the switch arms 49 and 50 are formed by resilient loops 54 and 55, respectively, to insure of effective contact for a sufficient length of time to operate the recording mechanism. These wiping elements, as well as the respective arms, are preferably formed of thin sheet metal having the desired resiliency.

Since the contacts which are made to operate the respective solenoid punches is to be of very short duration, and to prevent the wiper elements from stopping in engaged relation with the contacts 51 and 52, provision is made for snap action of the contact arms. This is provided preferably by pins 56 and 57 projecting laterally from the supports 53 in position to engage respective edge portions of the contact arms 49 and 50 and to pass through notches 58 and 59 formed in said edge portions as the arms move past the respective pins.

Since the ratchet wheels 43 and 44 are disposed oppositely, the sprocket 41 will drive only one ratchet wheel at a time, by engagement of the corresponding pawl 46 or 47 therewith upon rotation of the sprocket. The ratchet while not driven will be held frictionally in engaged position by a leaf spring 60 in frictional bearing relation therewith and mounted on the edge of the support 53, one such leaf spring being provided for each ratchet wheel 43 and 44.

Connected with the contacts 51 are wires 62, one of which extends to a source of electrical supply, such as a battery 63, while the other extends to one side of the solenoid designated 28d.

in Fig. 6, thence back to the source of electrical supply 63. This circuit will be closed whenever the ratchet wheel 43 turns through one revolution and causes the contact arm 49 to close the contacts 52 by the wiper 54. Such action will energize the solenoid 28d to actuate the punch thereof that will indicate the lowering of the drill stem in the well.

Where it is desirable to indicate only at extended intervals, for instance, ten feet, the depth of the well by the printing device 36, the solenoid 37 may be actuated only once for a plurality of closing actions of the switch 51-54, by providing a stepping switch in the circuit indicated at 64, leading to the solenoid 37 and which connects said solenoid with the source of supply 63 in parallel with the solenoid 28d. The circuit 64 is broken, however, except when closed at the stepping switch, the contacts of which are indicated at 65. This stepping switch may be of the form shown in Fig. 9.

A ratchet wheel 66 is rotatably mounted and carries a contact 67 in position to engage a spring support 68 on which one of the contacts 65 is mounted, so as to move the contacts 65 into engagement once for each revolution of the ratchet wheel 66 in the direction indicated by the arrow in Fig. 9.

The ratchet wheel 66 is held against accidental reverse movement by a resilient arm 69 which carries a roller 70 in position to engage spaced slots 71 formed in the ratchet wheel 66 at spaced intervals around its periphery corresponding with the steps of movement of the ratchet wheel.

The ratchet wheel 66 is actuated by a solenoid 72 which is adapted to reciprocate a pawl 73 against the tension of a spring 74. The pawl 73, each time the solenoid 72 is energized, is moved lengthwise to turn the ratchet wheel 66 through the distance of one tooth.

As shown in Fig. 6, the solenoid 72 is connected with the circuit 62 in parallel with the solenoid 28d so as to be energized each time that the solenoid 28d is energized. Thus the ratchet wheel 66 will be moved the distance of one tooth each time that the punching device 28d indicates that the drill stem has been lowered one foot for instance. Then upon the turning of the ratchet wheel 66 through one revolution, the circuit 64 will be closed at 65 to energize the solenoid 37, and cause the printing device 36 to print the total footage on the record strip 17.

A bell or other audible signal 75 is preferably connected in parallel with the circuit 64 to indicate to the driller the necessity of performing certain duties at intervals, such as taking a sample of formation that is being flowed up from the bottom of the well in the drilling mud.

A second stepping solenoid, generally indicated 60 at 76 actuates a ratchet 77 to close a switch 78, constituting a stepping switch similar to that described above and shown in Fig. 9, except that the ratchet wheel 77 preferably has many more teeth than the ratchet wheel 66. The solenoid 65 76 is connected in a circuit 79 controlled by the switch 52-55, actuated upon reverse movement of the sprocket 41 as in raising the drill stem.

This action will occur much more rapidly than the lowering movement during the drilling operation so that the indications need not be placed as closely together. Accordingly, it is preferable to have ninety teeth on the ratchet wheel 77, shown exaggerated in Fig. 6, so that the circuit will be closed at 78, for each ninety foot length of drill stem removed from the well.

The switch 78 controls a circuit 80 leading to a solenoid punch device 28c in Fig. 6, which is adapted to punch an indication in the appropriate column of the record strip 17 under "Raising Drill Stem."

It is preferable to have a switch 81 connected in the circuits 62—79, so as to de-energize the circuits 62 and 64 when the drill stem is being removed from the bore hole of the well. When the switch 81 is in the full line position in Fig. 6, the circuits 62 and 64 may be energized while the circuit 79 is deenergized. However, when moved to the dotted line position therein, the latter may be energized, but the former may not.

The punching devices 28a and 28b are adapted to be energized, respectively, to indicate the revolutions of the rotary table 8 and of the mud pump 10, which are provided with a control switch indicated at 82a and 82b, respectively, in Fig. 6, adapted to be closed once for each revolution of a control element, one form of which is shown in Figs. 10 and 11.

As shown in Fig. 10, the element 82 is in position to engage and close a pair of contacts 83, each time that the element 82 brushes past the contacts. This element is carried by a spring contact arm 84 fixed on a shaft 85 which has a geared connection within a housing 86 with a shaft 87, that is so connected with the power shaft of the rotary or of the mud pump as to make one revolution therewith. The shaft 85 may be geared in any desired ratio with such power shaft, as, for instance, 1 to 100.

The contact member 82 will engage the contacts 83 once for each revolution of the shaft 85. To provide a snap action for this engagement, I have provided a pin 88 in the path of an edge portion of the spring contact arm 84 and in position to pass through a notch 89 in said arm to provide a brushing contact with the contacts 83 as the arm moves thereby. As such snap action occurs, a wedge 90 positioned at the lower end of a stop post 91 will engage the contact arm 84 and hold it against vibrating movement as well as accidental bending back into engagement with said contacts.

The operation of the mechanism will be evident from the foregoing description so that repetition thereof will not be required.

It will be evident that the recording device 14 will be put into operation as the drilling progresses and the drill stem is moved gradually downward in the well. The respective punching devices 28a—28d (Fig. 6) will be actuated automatically at regular intervals in accordance with the operation of the drilling mechanism to record on the strip 17, the information desired by the driller, substantially as described above. The record sheet 17 will show to the driller the speed of operation of the rotary table and mud pump, as well as (by the spacing of the punch holes) the speed at which the drilling is progressing into the formation, as well as the depth of the hole. This will enable him to judge by an inspection of the record sheet the efficiency of the operation, as well as the character of the formation, inasmuch as drilling progresses more swiftly in some formations than in others.

It is to be understood that the recording device is also set in operation as the drill stem is removed from the well, the solenoid recording the travel of the drill stem, either up or down. It may be de-energized by the switch 81 moved into a neutral position midway between the contact points. The solenoid 28a and 28b prefer-

ably will be left in an operative condition at all times, so, in the event of circulation of mud through the drill stem or the rotation of the rotary table is occasioned at any point in the well, this will be recorded. Often in removing the drill stem from the well, or upon inserting it into the well, cavings will occur in the well, therefore, it is necessary to rotate the drill stem and circulate the mud therethrough, whereby this information will be recorded accurately upon the log strip for future reference.

While this invention has been described in detail with respect to particular recording devices, it is recognized that the types of these devices and their correlation may be varied materially. Therefore, the invention should not be limited to the form shown in the drawings, except insofar as is set forth in the claims.

I claim:

1. In combination with a rotary drilling rig, a rotary table, means for operating said rotary table, a pump for circulating hydraulic fluid in a well, means for operating said pump, a derrick carrying a stationary sheave journaled on said derrick, a cable passing over said sheave and said cable supporting a drill stem, said drill stem passing through said rotary table and slidably and rotatably connected therewith, of a chronologically operated mechanism for operating a record strip, a revolution counter connected to said pump for determining the revolutions of said pump, an electrical contact on said revolution counter within a circuit leading to said recording mechanism, and an electro-magnetic perforator for perforating said record strip in accordance with the revolutions of said pump.
2. In combination with a rotary drilling rig, a rotary table, means for operating said rotary table, a pump for circulation of hydraulic fluid in a well, means for operating said pump, a derrick carrying a stationary sheave journaled on said derrick, a cable passing over said sheave, means for operating said cable and said cable supporting a drill stem, said drill stem passing through said rotary table and slidably and rotatably connected therewith, of a chronologically operated recording mechanism for operating a record strip, said sheave having electrical connections operatively connected therewith and to a recorder to record the lineal travel of a cable passing thereover, and electro-magnetic punch for perforating said record strip at timed intervals in relation to the travel of the cable over said sheave, and a cooperating imprinting device co-ordinated with said electro-magnetic punching mechanism to imprint numbers or symbols on said record strip in coordinated timed relation to said electro-magnetic punch.

3. In combination with a rotary drilling rig, a rotary table, means for operating said rotary table, a pump for circulating hydraulic fluid in a well, means for operating said pump, a derrick carrying a sheave, a cable passing over said sheave, means for operating said cable and said cable supporting a drill stem, said drill stem passing through said rotary table and being slidably and rotatably connected therewith, of recording mechanism including a record strip, means for moveably supporting said record strip, an electrical contact mechanism operatively connected to said sheave for operation in one direction and inoperative in the opposite direction of said sheave, a multiple accumulator switch in a circuit and connected with said electrical contact mechanism, a second circuit op-

erated by said multiple accumulator switch, and an electro-magnetically operated perforator operatively connected to said multiple accumulator switch for perforating said record strip.

4. In combination with a rotary drilling rig, a rotary table, means for operating said rotary table, a pump for circulating hydraulic fluid in a well, means for operating said pump, a derrick carrying a sheave, a cable passing over said sheave and said cable supporting a drill stem, said drill stem passing through said rotary table and slidably and rotatably connected therewith, of a chronologically operated mechanism for operating a record strip, means operated by the drill stem supporting cable responsive to downward movement of the drill stem and inoperative by upward movement of the drill stem for applying indicia on the record strip of the depth of the drill stem in the well, means operated by the drill stem supporting cable responsive to upward movement of the drill stem and inoperative by downward movement of the drill stem for applying indicia on the record strip of the depth of the drill stem in the well, means operated by the pump for applying indicia of the pump speed on the record strip adjacent the depth indicia, and means operated by the rotary table driving means for applying indicia of the table speed on the record strip adjacent the depth indicia.

5. In combination with a rotary drilling rig, a rotary table, means for operating said rotary table, a pump for circulating hydraulic fluid in a well, means for operating said pump, a derrick carrying a sheave, a cable passing over said sheave and said cable supporting a drill stem, said drill stem passing through said rotary table and slidably and rotatably connected therewith, of a chronologically operated mechanism for operating a record strip, electrically operated means controlled by the drill stem supporting cable responsive to downward movement of said drill stem for applying indicia on the record strip of the depth of the drill stem in the well, electrically operated means controlled by the drill stem supporting cable responsive to upward movement of the drill stem for applying indicia on the record strip of the depth of the drill stem in the well, electrically operated means controlled by the pump for applying indicia of the pump speed on the record strip adjacent the depth indicia, and electrically operated means controlled by the rotary table driving means for applying indicia of the table speed on the record strip adjacent the depth indicia.

6. In combination with a rotary drilling rig, a rotary table, means for operating said rotary table, a pump for circulating hydraulic fluid in a well, means for operating said pump, a derrick carrying a sheave, a cable passing over said sheave and said cable supporting a drill stem, said drill stem passing through said rotary table and slidably and rotatably connected therewith,

of a chronologically operated mechanism for operating a record strip, a plurality of electrically operated devices arranged in side-by-side relation adjacent said record strip operating mechanism in positions for applying respectively indicia to the record strip representing the depth of the drill stem in the well, circuit closing means for each of said electrically operated devices in position to be actuated respectively by the drill stem supporting cable, mechanical means operated by said drill stem supporting cable, effective upon downward movement of the drill stem for actuating one of said circuit closing means, and effective upon upward movement of said drill stem for actuating another of said circuit closing means.

7. In well recording mechanism, adapted to simultaneously record the depth of penetration of the drill stem, and the speeds of a well pump and a rotary table, during a well-drilling operation, and to record the length of the drill stem during the removal of the same from the well, the combination of means for advancing a record strip, a plurality of depth indicia applying devices arranged in side-by-side relation, adjacent to the record strip advancing means in position for applying to the record strip indicia of the depth of a drill stem, means adapted to be actuated by downward movement of said drill stem for actuating one of said depth indicia applying devices, means adapted to be actuated by upward movement of said drill stem for actuating another of said depth indicia applying devices, pump and rotary table speed indicia applying devices positioned in side-by-side relation adjacent to said depth indicia applying devices, means adapted to be actuated respectively by said pump and rotary table for operating said speed indicia applying devices, and means rendering said depth indicia applying devices and said rotary table speed indicia applying devices ineffective during the removal of the drill stem from the well.
